UNITED STATES PATENT OFFICE.

FELIX PRZYBYSZ, OF JOLIET, ILLINOIS.

SOLDIER'S HEADWEAR.

1,299,611.

Specification of Letters Patent.

Patented Apr. 8, 1919.

Application filed March 23, 1918. Serial No. 224,298.

To all whom it may concern:

Be it known that I, FELIX PRZYBYSZ, a citizen of Poland, residing at Joliet, county of Will, and State of Illinois, have invented 5 certain new and useful Improvements in Soldiers' Headwear, of which the following is a specification.

This invention relates to improvements in armored devices for protecting the head and 10 face of a wearer and particularly adapted for the use of soldiers.

The principal object of the invention is to provide a protective cap, casque or helmet capable of diverting projectiles, sword 15 thrusts and the like so that the wearer's face and head is maintained in a safe condition.

A further object is to provide means whereby a flexible, shawl-like element, also of a protective nature, is engaged at the 20 rear of the casque covering the sides of the head and shoulders of the wearer.

A still further object is to provide means whereby the voice is not impeded and openings provided through which a view may be 25 taken by the wearer.

These and other like objects are attained by the novel construction and combination of parts hereinafter described and shown in the accompanying drawing, forming a material 30 part of this disclosure, and in which:—

Figure 1 is a perspective view indicating the application of the invention from the rear.

Fig. 2 is a similar perspective view taken 35 from the front, and

Fig. 3 is a vertical sectional view taken substantially on the center line from front to back of the same.

The device and its component parts are 40 made of a suitable, non-puncturable and bullet-resisting material, preferably metal as it is used nowadays in the manufacture of trench, or shrapnel-proof helmets.

The device comprises the concavo-convex 45 upper portion or crown 10, formed in the shape of a hat, to which is rigidly engaged, by rivets 11, a flange 12, formed with a rim, bent downwardly at the back 14, and extended horizontally outward at the front 50 visor portion 15.

Secured by other rivets 17 is an arcuate flange 18, formed with the rigid sides 20 which extends in a semi-circle below the crown 10, the rear portion 21, of the material 55 of the crown extending slightly downward below the joint of the rim 14 and has

engaged with it a plurality of flexibly united, metallic scale-like elements forming a hood 22, adapted to be disposed over the shoulders and portion of the back of the 60 wearer, the same being attached by fastenings 24, to the edges of the plates 20, which form the cheek portions of the device.

Secured by hinges 26 is a door 27, a pivoted clip 28, being arranged from the opposite side of the door, so as to secure the same when in a closed position. This door is set within the side elements 20, and slightly below the flange 18, so as to swing outwardly 70 therefrom at any desired moment.

In the door are openings 30 for the eyes, below which is an outwardly formed projection 31, for the nose, while an opening 32 permits the lips to be used when it is desired to talk. This opening is normally covered 75 by a pair of shutters 33, movable in guides 34, fixed within the interior of the door and operable by extending knobs 35, so that two parts of the shutter may be separated when it is desired to use the door for receiving 80 food or for the purpose of conversation.

The application of the invention is believed to be self-evident from the foregoing description, taken in connection with the drawings, and it will be seen that an effective 85 device has been presented which will divert projectiles or the like and prevent them from doing injury to the wearer of the device.

I claim:—

1. A cap comprising non-puncturable helmet, a brim extending therefrom, side plates rigidly engaged with said brim, a door set in said side plates, openings for the eyes, nose and mouth formed through said door, 95 means for closing said mouth opening, and a flexible element comprising a plurality of metallic scales, united to said plate below the brim of the helmet at the rear thereof.

2. In a soldier's cap, the combination with 100 a rigid non-yielding crown, a brim riveted thereto, said brim extending horizontally outward at the front and turned downward at the rear, side plates formed with said brim extending along the cheeks of the 105 wearer, a door hinged between said side plates, means for holding said door in a closed position, openings formed through said door for the eyes, nose and mouth of the wearer, means for closing the openings 110 for the mouth, and a flexible shield united to said side plates and to said brim, said

shield being comprised of a plurality of inter engaged, metallic, scale-like elements adapted to be disposed over the shoulders and upper portion of the back of the wearer.

5 3. In a soldier's cap, the combination with a head covering, side walls depending therefrom, and a door hingedly engaged between said side walls, said door opening outward, of a plurality of interengaged flexible scale-

like metallic elements secured to the opposite edges of said side plates and to said rim, said scale elements being formed in the manner of a hood adapted to cover the shoulders and upper portion rear of the wearer.

In testimony whereof I have affixed my 15
signature.

FELIX PRZYBYSZ.
